UNITED STATES PATENT OFFICE

154,773

DESIGN FOR A RAILWAY LOUNGE VEHICLE

Ralph W. Haman, Flossmoor, and Stanley W. Kay, Chicago, Ill., assignors to Pullman-Standard Car Manufacturing Company, Chicago, Ill., a corporation of Delaware

Application August 10, 1946, Serial No. 132,422

Term of patent 14 years

(Cl. D66—1)

To all whom it may concern:

Be it known that we, Ralph W. Haman, and Stanley W. Kay, citizens of the United States and residents, respectively, of Flossmoor, county of Cook, and State of Illinois, and Chicago, county of Cook, and State of Illinois, have invented a new, original, and ornamental Design for Railway Lounge Vehicle, of which the following is a specification, reference being had to the accompanying drawings, forming part thereof.

Fig. 1 is a general plan view of a portion of a railway vehicle of our new design showing the interior arrangement in this portion of the vehicle;

Fig. 2 also is a general plan view, but illustrating the opposite portion of the vehicle complementary to that indicated in Fig. 1 and showing the interior arrangement in this portion of the vehicle;

Fig. 3 is a general perspective view of that portion of the vehicle illustrated in Fig. 1, and having portions broken away better to reveal the interior arrangement;

Fig. 4 also is a general perspective view, but illustrating the portion of the vehicle shown in Fig. 2 and having portions broken away to disclose the arrangement of the interior;

Fig. 5 is a general perspective view of a conventional railway car body of the type in which our new design is incorporated, and indicating the supporting trucks in dotted lines;

Fig. 6 also is a general perspective view similar to Fig. 4, but to larger scale and showing the interior arrangement in greater detail; and

Fig. 7 is a detail perspective view, also to larger scale, showing an intermediate portion of the vehicle interior arrangement.

The characteristic features of the present design are shown by means of full lines in the drawings and reside in the living room arrangement in the interior portions of the vehicle, wherein lounge chairs and associated leg rests are shown in dotted lines in the several drawing figures, for purposes of illustration.

We claim:

The ornamental design for a railway lounge vehicle, substantially as shown and described.

RALPH W. HAMAN.

STANLEY W. KAY.
